UNITED STATES PATENT OFFICE.

EMIL ZIMMERMANN, OF NEW YORK, N. Y.

WORK-SUPPORT FOR LATHES.

SPECIFICATION forming part of Letters Patent No. 340,535, dated April 20, 1886.

Application filed February 2, 1886. Serial No. 190,583. (No model.)

To all whom it may concern:

Be it known that I, EMIL ZIMMERMANN, of the city of New York, county and State of New York, have invented a new and Improved 5 Work-Support for Lathes, of which the following specification is a full, clear, and exact description.

This invention relates to a rest for supporting the work while being turned in a lathe 10 and preventing the same from sagging. The rest or support is vertically adjustable, and is constructed with a view to permitting the free rotation of the work.

The invention consists in the elements of improvement hereinafter more fully pointed out.

In the drawings, Figure 1 is a sectional side view of my improved work-support for lathes. Fig. 2 is a section through the collar on line x x , Fig. 5; Fig. 3, a side view of the collar when 2c open. Fig. 4 is an end view of the work-support for lathes, and Fig. 5 an end view of the collar.

The letter a represents an upright post, screw-threaded near its upper and lower ends, and 25 connected at its upper end to a sectional ring, b . The two sections of this ring are hinged together at one end, while their free ends are provided with outwardly-projecting lugs c , which have screw-threaded perforations for 30 the reception of a thumb screw, d , by means of which the sections may be firmly locked together. The ring b contains an annular collar, e , adapted to turn within ring b , and in turn to receive the work. The collar e is also made 35 in two sections, so that it may be opened or closed. Each section has two side lugs at one end and a central lug at the other end. The side lugs of one section embrace the central lug of the other section, and by passing a pin 40 through the lugs the sections are properly locked together.

f are headless screws passing through collar e and bearing with their inner ends against the work, so that the collar may be clamped to and rotate with the work. There is no 45 tendency of the collar e to slip out of ring b , and no means for preventing lateral displacement of the collar are therefore shown in the drawings; but, if desired, the collar may be provided with a surrounding annular groove, 50 for the reception of the end of a pin or setscrew passing through the ring. The post a is embraced by a block, g , which has an offset, h , near its lower end, so as to set upon the side pieces or bed, i , of the lathe. At its upper end the block g has a screw-threaded head, j , while a winged nut, k , that embraces the lower end of post a , bears against the lower end of the block. If the work-support is to be elevated, the post a is screwed up and fastened in position by the winged nut k . To 60 lower the work-support, the post is screwed down and the nut is then screwed up.

I claim as my invention—

1. The combination of post a , carrying sectional ring b , with the collar e , provided with adjusting-screws f , substantially as specified.
2. The combination of screw-threaded post a , carrying sectional ring b , having lugs c and screw d , with the collar e , having screws f , 70 and with the block g , that embraces post a , substantially as specified.
3. The combination of screw-threaded post a , ring b , and collar e , with the block g , having offset h , and perforated head j , and with the 75 winged nut k , substantially as specified.

EMIL ZIMMERMANN.
